UNITED STATES PATENT OFFICE.

ALBERT SCHMID, OF PITTSBURG, PENNSYLVANIA, ASSIGNOR TO THE WESTINGHOUSE ELECTRIC COMPANY, OF SAME PLACE.

ARMATURE-CORE FOR DYNAMO-ELECTRIC MACHINES.

SPECIFICATION forming part of Letters Patent No. 361,896, dated April 26, 1887.

Application filed July 29, 1886. Serial No. 209,366. (No model.)

To all whom it may concern:

Be it known that I, ALBERT SCHMID, residing at Pittsburg, in the county of Allegheny and State of Pennsylvania, a citizen of the 5 United States, have invented or discovered certain new and useful Improvements in Cores for Armatures, of which improvements the following is a specification.

In the accompanying drawings, which make 10 part of this specification, Figure 1 is a central sectional view of my improved armature-core for dynamo-electric machines, showing the arrangement of the disks and retaining-plates. Fig. 2 is an end elevation of the core. 15 Fig. 3 is a sectional detail view showing the manner of insulating the disks forming the core of the armature.

Heretofore in forming the cores for the armatures for dynamo-electric machines the 20 metal disks composing the core were stamped out of suitable sheet metal, and when arranged on the shaft were turned off on their outer edges to produce a true cylindrical surface. As, however, the disks were formed of soft 25 metal, fins would be formed at their edges, and by the action of the cutting tool would be bent over, and, bridging the intervening insulating sheets or disks, would form electrical connection with the adjoining metal disk, thereby 30 destroying the effectiveness of the armature.

The object of the invention herein is to so form the metal disks as to avoid the necessity of subsequent turning or trimming in order to bring the disks to a uniform size when placed 35 in the shaft; and it is a further object of said invention to protect the edges of the disks as against any liability of adjacent disks being electrically connected.

In general terms, the invention consists in 40 the construction and combination of parts, substantially as hereinafter described and claimed.

In manufacturing my improved core, sheets 45 of any suitable metal are first centrally punched to form the holes for the reception of the shaft 1, and the sheets are then placed in a rotary shears and cut into disks of a uniform diameter, thus insuring a uniform diameter of core when the disks are arranged on the shaft, without 50 resorting to subsequent trimming or turning

in a lathe. In arranging the parts to form the core a retaining-disk, 3, is first slipped onto the shaft up to the shoulder 4, and there secured as against rotation on the shaft by a key, 5. (See Figs. 1 and 3.) A disk, 6, of 55 insulating material, is then placed next to the disk 3, then one of the metal disks 2, and next an insulating-disk, 6, and so on until about midway of the length of the core. At this point another retaining-disk 3 is placed. The re- 60 mainder of the core is made up of alternate disks of metal and insulating material, as shown, the whole being held together by another retaining-disk 3 and a nut, 7, screwing onto the shaft and forcing all the disks firmly 65 together. The outer retaining-disk 3 and the 70 nut 7 are locked as against movement around the shaft by the screw 8, passing partially through the disk and nut and screwing into the shaft 1.

The insulating disks 6, which may be formed of paper or other insulating material, are of a diameter sufficiently greater than the diameter of the metal disks 2 to cause them to project a short distance beyond the edges of the 75 metal disks, as shown in Fig. 3, and previous to their being placed in position between the metal plates are saturated with shellac, glue, &c. After the metal and insulating disks have 80 been placed together, as above described, the projecting edges of the insulating disks are folded down over the peripheries of the disks 2, as shown in Fig. 3.

The insulating disks project sufficiently beyond the disks 2 to lap one upon the other 85 when folded as above stated, thus completely covering and protecting the edges of the metal disks, the overlapping edges being secured together by the shellac or glue.

A series of pins, 9, are inserted in the peripheries of the retaining-disks 3, said pins serving to hold the wires which are wrapped around the core in place.

I claim herein as my invention—

1. A core for armatures having in combination a series of metallic disks and a series of insulating-disks arranged between the metallic disks, the edges of the insulating-disks being folded down over the edges of the metallic disks, substantially as set forth. 95 100

2. A core for armatures having in combination a series of metallic disks and a series of insulating-disks arranged to alternate with the metallic disks, the edges of the insulating-disks projecting beyond the edges of the metallic disks, thereby insuring the perfect insulation of each metallic disk from those adjacent thereto, substantially as set forth.
5. A core for armatures having in combination the retaining-disks 3, provided with radially-projecting pins, a series of metal disks,
3. A core for armatures having in combination the retaining-disks 3, provided with radially-projecting pins, a series of metal disks,

2, and a series of insulating-disks arranged between the metal disks, the edges of the insulating-disks being folded down over the edges of the metallic disks, substantially as set forth. 15

In testimony whereof I have hereunto set my hand.

ALBERT SCHMID.
